US0D1072528S

(12) **United States Design Patent** (10) **Patent No.:** **US D1,072,528 S**
(45) **Date of Patent:** **** Apr. 29, 2025**

(54) **AIR BED**

(71) Applicant: **Yunxiao Li**, Zhoukou (CN)

(72) Inventor: **Yunxiao Li**, Zhoukou (CN)

(**) Term: **15 Years**

(21) Appl. No.: **29/896,766**

(22) Filed: **Jul. 7, 2023**

(51) LOC (15) Cl. **06-09**

(52) U.S. Cl.

USPC **D6/604**

(58) **Field of Classification Search**

USPC D6/595, 596, 601, 604, 605, 606;
D24/191, 192, 178

CPC A47G 9/10; A47G 9/1009; A47G 9/1027;
